UNITED STATES PATENT OFFICE.

WILLY KRAATZ, OF KREUZNACH, GERMANY.

DESIGN FOR A WEIGHING-MACHINE CASE.

Application filed October 10, 1925. Serial No. 15,083. Term of patent 7 years.

To all whom it may concern:

Be it known that I, WILLY KRAATZ, a citizen of the German Empire, residing at 50 Wilhelmstrasse, Kreuznach, Rhld., Germany, have invented a new, original, and ornamental Design for Weighing-Machine Case, of which the following is a specification, reference being had to the accompanying drawing, forming part thereof.

The figure is a perspective view of a weighing machine case, showing my new design.

I claim:

The ornamental design for a weighing machine case, as shown.

WILLY KRAATZ.
